CLAIM

The ornamental design for a medical device for positioning patients, as shown and described.

DESCRIPTION

FIG. 1 is a back, top, left perspective view of a medical device for positioning patients in an open position;
FIG. 2 is a front, bottom, right perspective view of the medical device for positioning patients of FIG. 1;
FIG. 3 is a top plan view of the medical device for positioning patients of FIG. 1;

FIG. 4 is a bottom plan view of the medical device for positioning patients of FIG. 1;

FIG. 5 is a left side elevation view of the medical device for positioning patients of FIG. 1;

FIG. 6 is a right side elevation view of the medical device for positioning patients of FIG. 1;

FIG. 7 is a front elevation view of the medical device for positioning patients of FIG. 1;

FIG. 8 is a back elevation view of the medical device for positioning patients of FIG. 1; and,

FIG. 9 is a back, top, left perspective view, in a closed position, of the medical device for positioning patients of FIG. 1.

The broken lines in the drawings depict portions of the medical device for positioning patients that form no part of the claimed design.
